PISTON SKIRT EXPANDER

Albert W. Wenzel, Paterson, N. J.

Application November 2, 1935, Serial No. 48,042

4 Claims. (Cl. 309—12)

My invention relates to new and useful improvements in piston skirt expanders, and has for an object to provide a means for efficiently expanding the skirts of new or worn pistons. If 5 new pistons are to be used in slightly worn cylinders, it is desirable that the skirt be expanded. Also, old or slightly worn pistons have a tendency to piston slap, and if the skirt is expanded, this, in a good many instances, will be overcome.

10 One of the principal objects of the invention is to provide a piston skirt expander comprising substantially a properly tempered spring wire element having two arms and an eyelet or loop formed integral therewith, so that the arms may 15 be fitted into one portion of the split skirt and the loop or eyelet secured to the opposite (adjacent) portion of the skirt. Thus, there will be a spreading action provided which, although relatively light, will tend to spread the skirts an 20 additional five to twenty ten-thousandths which usually is sufficient to prevent the objectionable slapping of the piston.

Still another object of the invention is to provide a piston skirt expander, preferably made 25 of one piece of wire which is bent to provide two arms with offset ends and also bent to provide an integral eyelet, the latter spaced centrally of the arms and to the rear thereof, as shown in the preferred form. Again, the expander may 30 be formed by bending the arms inwardly and then in an offset plane to form a retaining loop, as shown in one of the modifications. Further, the expander may comprise a single piece of wire bent with a double curve centrally of its 35 length and then outwardly toward the opposite ends to form two diverging arms, as shown in another modification.

Still another object of the invention is to provide an especially resilient form of skirt expander 40 and to also provide a very efficient means for holding the expander in position. In either the preferred or the modified forms, the central portion of the expander, that is, either the loop or the eyelet or the double curve, is secured to one 45 portion of the split skirt, while the ends of the resilient arms are fastened in the other portion of the split skirt, thus providing the desired spreading action at all times.

In the drawing showing a preferred embodiment and two slight modifications,

Fig. 1 is a detailed elevation of the preferred form of piston skirt expander, showing a piece of wire bent to form the two arms and an integral eyelet;

Fig. 2 is a front end view of the same;

Fig. 3 is a side elevation, partly in section, of a piston showing the skirt expander secured in position, the arms being also shown in dotted lines in the position which they will assume before being retained in their receiving apertures;

Fig. 4 is a detailed sectional view taken on the line 4—4 of Fig. 3;

Fig. 5 is an end view of a slightly modified form of piston skirt expander;

Fig. 6 is a view similar to Fig. 3, showing the 5 manner of retaining the expander shown in Fig. 5 in position;

Fig. 7 is a sectional view taken on the line 7—7 of Fig. 6; and

Fig. 8 is a fragmentary detailed view of a fur- 10 ther modification of the expander and the means for holding the same in position.

Referring now more particularly to the several views, and to Fig. 3 for the moment, there is shown a piston block 1, comprising the head portion 2, with the annular grooves 3 for the reception of the piston rings and oil rings. There may also be seen the skirt 4 with the bearings 5 therein for the reception of the wrist pin of a connecting rod (not shown), and it will be noticed 20 that the skirt is split, there being the vertically extending slot 6.

It will be understood that I do not wish to be limited to the specific manner in which the skirt is split, as these piston skirt expanders may be 25 very efficiently used with various forms of split skirt pistons.

Having referred briefly to the piston, reference is now made to the skirt expander per se.

Referring to Fig. 1, there is shown a preferred 30 type of expander, made from resilient wire, which, after being bent to form, is properly hardened and tempered. It will be seen that it consists of one piece or section of wire which is bent to form the arcuate arm 7 and the correspondingly bent arcuate arm 8, the arms being then twisted about each other, as at 9, and then bent to form the eye or eyelet 10. The outer ends 11 of the arms 7 and 8 are then bent at right angles to the plane of the open-face eyelet, as 40 may be seen in Fig. 2.

It will be understood, of course, that both the preferred and modified forms of skirt expanders will be made on jigs, and the sequence of bending above set out is simply for the purpose of 45 clearness of description.

Now in Fig. 4, there is shown a stud S, preferably one piece, having the barrel or pin 12, the slightly enlarged central portion 13, and the enlarged head 14.

In the piston are drilled two apertures 11', both on one side of the slot 6, while diagonally opposite from these apertures in the other portion of the skirt, that is, on the opposite side 55 of the slot 6, there is also drilled an opening or aperture 12' to receive the barrel 12 of the stud S. This aperture 12' should provide what is technically known as a "drive fit" for the pin or barrel 12 of the stud.

After the stud is positioned within its aperture, the end of the stud may be peened or headed, but care should be taken that the stud does not extend beyond the outer surface of 5 the piston wall, as if this were so, it would tend to score the cylinder.

To apply the piston expander, therefore, it will be seen that the eyelet 10 will be placed over the aperture 12' within the piston and the 10 stud then driven or riveted in place, thus tightly securing the expander in position.

After this, the arms 11 will be pulled toward the eyelet until the ends 11 snap within the apertures 11' which, it will be remembered, are on 15 the opposite side of the slot 6.

Thus, it will be seen that there will always be a spreading action caused by this piston expander, the two arms tending to force one portion of the skirt away from the portion to which 20 the eyelet is attached.

Should it so happen that the piston skirt expander break, it is but the matter of a moment to drive out the stud and rivet a new one in position.

25 It will also be seen that by forming a piston skirt expander in this manner, that is, by twisting or intertwining the arms, at 9, there is less likelihood of the two arms 7 and 8 snapping or breaking, as there are no sharp bends to fatigue 30 the metal during the formation of the expander.

Referring now to a slightly modified form, and to Figs. 5 to 7, inclusive, there is also shown a piston block 15 with its skirt 16, bearings 17, and the vertical slot 18 in the skirt. There is 35 further shown a wire piston skirt expander 19, and in this instance the expander has the diverging arms 20 and 21 with the outer ends 22 extending in a horizontal plane therefrom, the arms 20 and 21 at their inner ends extending 40 transversely and merging in the offset loop or bend 23.

Now to position this expander, a small recess 24 (see Fig. 7) is cut in the inner surface of one wall 23' of the skirt adjacent the vertical slot 18, while riveted thereover, as at 25, in the 45 opposite skirt wall 25' is a small tongue 26 to prevent the expander from springing outwardly. In a like manner, there are two apertures 22' formed in the skirt 25', so that these arms may 50 be pulled toward the loop portion 23 until they spring into these properly positioned apertures 22'.

This form of piston skirt expander necessitates the cutting out of the aforementioned recess 24 in the inner wall of the skirt, rather 55 than drilling a hole or aperture, as shown at 12 in the preferred form. However, the expander with its fastening means of this species has proved very efficient in action.

60 Referring to a still further slightly modified form, there is shown in Fig. 8 the fragmentary portion 27 of a skirt, the slot 28, a plain stud 29, the two apertures 30, and the wire skirt expander 31.

65 In this instance, the expander 31 has the two outwardly extending arms 32, which diverge from the arcuate central portion 33, which latter portion bears, in turn, against the heretofore mentioned stud 29. The central portion is substantially in the form of an ogee curve, so that 70 there are no sharp bends to fatigue the metal.

The outer ends of the arms 32 will also be offset, as shown in the other forms, to be received in the two apertures 30.

It might be mentioned that the slots in the piston skirts, that is, the slot 6, as shown in 5 Fig. 3, the slot 18, as shown in Fig. 6, or the slot 28, shown in Fig. 8, have recesses 34 formed therein near their upper and lower ends, in which the respective spring arms may be sprung if it is desired to put a greater tension thereon to 10 thus more effectively separate the skirts of the piston.

It will also be understood that the respective apertures 11', 22', and 30 are not always absolutely necessary, as the apertures 34 may be used. 15 However, I have found it expedient to have these separate apertures in case it is not desired to have as great a tension on the arms as if they were sprung into the respective apertures 34.

As heretofore mentioned, these expanders are 20 all made on jigs and then properly hardened and tempered to provide the desired resiliency.

From the foregoing, it will be seen that I have designed a piston skirt expander that will overcome the objectionable piston slapping and that 25 I have also devised means for securely holding the same in place, so that there is no probability of their springing from their set position.

Furthermore, by constructing these expanders from one piece of wire and bending them in the 30 manner shown, any danger of fatiguing the metal during their formation is avoided.

It will be understood that I do not wish to be limited to the identical shape of the arms or necessarily to the number of arms used. 35

I am aware that it is old to provide piston skirt expanders of U-shape and other forms and am not claiming my invention as such, but what I do claim as new and desire to secure by Letters Patent is:—

1. A piston expander for a slotted piston having skirt portions one of which is apertured, comprising a spring member having a looped central portion and similar diverging arms extending from the looped central portion, the ends of the 45 arms being offset, said looped central portion being adapted to be fastened to one skirt portion of the piston with the offset ends of the arms adapted to be fitted within the apertures of the other skirt portion. 50

2. An expander for a slotted piston skirt comprising an eyelet portion formed of spring wire, two similar diverging integral arms twisted about each other adjacent the eyelet merging therewith and extending in opposite directions, and lugs 55 on the ends of the arms at right angles to the open face of the eyelet.

3. An expander for a slotted piston skirt consisting of a spring member bent centrally to form an eyelet, arms twisted at their inner ends about each other and merging with the eyelet, said arms being curved and diverging from the twisted ends and having lugs on their ends extending at right angles to the open faces of the eyelet. 60

4. A piston expander comprising a single strand of resilient wire provided with an attaching loop centrally thereof, a pair of similar arms diverging from the loop, said arms provided with offset ends. 65
